UNITED STATES PATENT OFFICE.

THEOPHILUS BROWN, OF MOLINE, ILLINOIS, ASSIGNOR TO DEERE & COMPANY, OF MOLINE, ILLINOIS, A CORPORATION OF ILLINOIS.

FLOW CONSTRUCTION.

Application filed October 10, 1921. Serial No. 506,672.

My invention relates to plows and more particularly to the manufacture of that type of plow having a plurality of plow beams and plow bodies. As one of the economies of manufacture it is necessary that the various parts included in a modern gang plow should have that degree of finish by which the parts can be assembled into a complete implement without alteration; the parts accurately fitted in proper relation with each other and the cutting edge of the plow shares presented in a true horizontal plane.

I have found that much of the hand fitting which may be necessary in assembling a multiple plow can be dispensed with by a proper construction of the plow beams, and as the beams and other parts of the plow are manufactured in large quantities, it is an object of my invention to produce a gang plow which can be readily assembled with the certainty of correct alinement of the parts without further fitting.

In the following specification I fully describe the various steps in the manufacture of a gang plow embodying my invention, following it from the stock bar, from which the beams are made, to the finished plow.

Referring to the drawings in which similar numerals indicate identical parts,

Figure 1 represents the stock bar from which the plow beam is made. Figure 2 illustrates the first step in manufacture from the plain bar. Figure 3 illustrates the second step with the bar lengthened and partly tapered. Figure 4 is a top view of Figure 3. Figure 5 shows the bar after the first bending. Figure 6 is a similar view to Figure 5 but showing the ends trimmed, and holes punched in which bolts or rivets are inserted in assembling the plow. Figure 7 is a bottom plan of Figure 6 showing its lateral bends and having its rear end of an ideal form and as it is prior to tempering. Figure 8 is a similar view to Figure 7 but showing the actual shape of the beam before the application of my improvements. Figure 9 is a bottom plan of two plow beams secured together and their rear ends warped. Figure 10 is an enlarged rear view of Figure 9. Figure 11 is a similar view to Figure 10 but having plow bodies secured to the beams and illustrating the position of the cutting edge of the shares before the application of my improvement. Figure 12 is a similar view to Figure 10 but embodying

my improvement and showing in dotted lines the position of the grinding wheels. Figure 13 is a plan view in part of Figure 12. Figure 14 is a similar view to Figure 11 but showing the perfect alinement of the cutting edge of the shares when the plow bodies are mounted on beams having my improvement, and Figure 15 is a side elevation of a grinder with a plow beam structure in place thereon for operation of the grinding wheels.

The stock bar 1, of high grade steel, from which the bar is made, is supplied in predetermined lengths preferably rectangular in cross section. To begin the manufacture of a plow beam one end 2 of the bar 1 is heated to the desired degree of malleability and, by forging, the groove 3 is formed and the adjacent opposite sides 4 of the bar are beveled, this operation slightly lengthening the bar. After further heating of the bar 1 for its entire length it is rolled to the form and length shown in Figures 3 and 4, the four sides tapering from approximately one third the length of the bar toward the forward end 5 thereof, and the intermediate third of its length is tapered forwardly on its landward and furrowward sides only. The bar 1 is now ready for transformation into the beam 6 which is accomplished, after again heating it, by operation of a bulldozer bending it to form a standard to support a plow body, as shown in Figure 5. From the bulldozer the beam is transferred to a machine operating to simultaneously punch all bolt and rivet holes and trim the ends of the beam as shown in Figure 6. After this latter operation the beam is bent laterally at 7 and 8 to give it a final form, as shown in Figure 7, previous to the hardening process.

The beam is now heated to a specific degree above its critical point, and is then removed from the furnace and immersed in a quenching bath for a predetermined period of time to harden and toughen it, the beam is then raised from the bath and placed in a drawing furnace where it is subjected to a specific degree of heat for a certain time, to remove strains produced by the effect of the quenching bath, and at the expiration of that time is slowly cooled.

A warp is likely to occur at the rear of each beam, while the latter is in the quenching bath, whereby the downwardly extending portion or standard 10 will assume a position laterally to one side or the other

of the beam. It is impossible to forecast where and toward which side of the beam the warp will occur, and after it has formed it is practically impossible to correct it by 5 side pressure without heating again and destroying the temper. It will be readily apparent that if a plow body should be mounted on a beam at this time it would result in the condition shown in Figure 11 where two 10 beams are illustrated, both warped, but in opposite directions, the share of the plow body on the beam 6 having its cutting edge at an angle below a horizontal plane, and the share of the plow body on the beam 9 15 having its cutting edge at an angle above a horizontal plane. This is an ever present defect, and has heretofore never been completely remedied except by expenditure of extra time and manual labor on each individual plow, adding materially to the cost 20 of manufacture and lessening speed of production. Heretofore in the construction of a gang plow it has been the practice to secure the beams to the plow bodies irrespective of 25 the warp in the beam, the plow bodies, during the operation, resting upon a plane table, and it is obvious that with a plurality of beams and plow bodies so secured together with the warp still in the beams, the braces 30 holding the beams in rigid relation with each other would have to be shaped by repeated heating to fit the beams, for as the degree of warp would likely be different in each beam, standardization of the braces was im- 35 possible, consequently it was necessary to fit each brace to the plow beams, requiring an excess of labor and time expended in the operation.

In Figure 9 I have shown two plow beams 40 6 and 9 spaced apart and rigidly secured together by braces 10^a and 11, the forward ends of the beams converging to a clevis plate 12 and secured thereto by rivets. The beams and braces are of standard form and 45 are taken from stock and assembled without further fitting, the braces being bent and bolted to the intermediate parts of the beams. The warp in the beams remains, however, as clearly shown in Figures 9 and 50 11, and as shown is in opposite directions; the true vertical planes in which the rear ends or standards of the beams should be are indicated by dotted lines. As it is impossible to force the standards to these lines, 55 and in order to secure a true vertical surface otherwise, I subject the sides of the standards 10, on which the plow bodies are to be mounted, to the operation of a grinder *a*, the grinding wheels *b* and *c* of which are spaced apart to operate for the proper width 60 between the plow bodies; the beams, as secured together, are placed in the grinder, with the front end held in a support *d*, and sufficient of the sides of the standards, on 65 which the plow bodies are to be mounted,

is cut away to a true vertical surface, irrespective of the degree of warp, as shown at 13 and 14 in Figure 12. It will be understood that should any plow body support of an assembled beam frame already present 70 a proper positioning surface to receive the plow body, the removal of material from that beam support would not be necessary, since the purpose of the removal of the material is to make the positioning surface of 75 each of the plow body supports of a given beam frame conform to a predetermined standard adopted for the corresponding support of other similar frames. My invention, therefore, does not contemplate the removal 80 of material from each and every support in all instances, but only where and to the extent necessary to accomplish the desired result. In the illustrated embodiment of my invention the plow bodies are of a well 85 known type and comprise a moldboard 15, a share 16, and a frog 17, the latter being securely bolted to the sides of the standard ground to a true vertical plane, so that the plow, as assembled, presents the cutting 90 edge of the shares in perfect horizontal alinement as shown in Figure 13.

From the foregoing it is apparent that the beams and braces can be manufactured in quantities and assembled and secured rigidly together for reception of plow bodies, and held in stock to be drawn from as desired. It is also true that the parts composing the plow bodies are manufactured, and assembled and placed in stock, but in every 100 instance the frogs designed to be attached to the positioning surface of a given plow body support, are so shaped that when attached to such support the plow body will be securely held so that its landside is in a true 105 longitudinal vertical plane, and consequently the plow bottom lies in a horizontal plane. It will be obvious, therefore, that when the several plow bodies are attached to the beams of any frame, the plows will be properly positioned relatively to each other, with the planes of their landsides parallel, notwithstanding the fact that the beams as originally assembled may have been warped so that except for the cutting away or removal, as by grinding or equivalent means, 110 of the plow body positioning surfaces, as above described, the plow bodies would not be properly positioned relatively to each other or to a longitudinal vertical plane. It 115 will be understood, of course, that while it is desirable that the plow body positioning surfaces of all the supports of a given frame be formed so as to be parallel with each other and to lie in longitudinal vertical 120 planes, and to use frogs also having vertically disposed contact surfaces, this is not essential, as the same principle may be applied in other ways;—as for example, by 125 making the positioning surfaces of the plow 130

body supports bear a predetermined angular relation to a horizontal or vertical plane, and fashioning the contacting surfaces of the frogs, or other connecting means by 5 which the plow bodies are secured to such supports, with complementary surfaces calculated to insure the proper positioning of the plow bodies when attached to such supports. Furthermore, it is not essential that 10 the positioning surfaces of all the plow body supports incorporated in the same frame be made parallel with each other, since by using with the positioning surfaces of such supports plow bodies provided with contacting 15 surfaces suitably designed for application thereto, the proper positioning of all the plow bodies attached to the same frame may be assured. By my invention therefore I make it practicable to manufacture plow 20 bodies having frogs, or other attaching devices, made according to a predetermined standard, with the certain knowledge that when such plow bodies are taken from stock and applied to a plow body support of the 25 character for which they are intended, they will invariably fit properly and be held in the right position.

While I have shown a frame comprising only two beams, it should be understood that 30 if desired more than two beams may be incorporated in the frame, and that part of the invention described which relates to insuring the proper positioning of the plow bodies is not limited to its application to 35 gang plow frames of the specific construction shown and described.

I wish it to be understood that by specifically describing the manufacture of the particular high grade steel beams illustrated 40 as entering into the construction of my improved gang plow frame, I have not intended to indicate that my invention may be practiced only in connection with gang plow frames comprising beams made of the 45 material mentioned, or beams that are tapered, or are of the cross-sectional contour shown, as obviously my invention may be applied to, or be practiced in connection with, gang plow frames having beams made 50 of other suitable materials besides high grade steel, either with or without heat treatment, and of any suitable shape; also the beams, including the plow-body supports, need not necessarily be made of integral bars, but may be of composite structure. In other words, my invention may be 55 used to advantage in connection with any plow frame comprising a plurality of metal beams provided with depending supports having plow body positioning surfaces 60

capable of being made to conform to a predetermined standard adopted for the positioning surfaces of the corresponding supports of other similar frames by the removal of material therefrom, as by grinding. The claims hereinafter made are, 65 therefore, to be construed accordingly.

By my invention I provide for making a perfectly true standardized gang plow frame all the parts of which are in true relation to 70 each other so that when predetermined frogs or other plow body securing elements are attached thereto the plows will also be in true plowing relation to each other.

What I claim is:

1. The improvement in the art of manufacturing gang plow frames which consists in removing material from the frame to such extent that when predetermined plow elements are attached thereto the plow bodies 80 will be in true plowing relation to each other.

2. The improvement in the art of manufacturing gang plow frames which consists in removing material from the plow body supporting portions of the frame to such extent that when predetermined plow elements are attached thereto the plow bodies 85 will be in true plowing relation to each other.

3. The improvement in the art of manufacturing gang plow frames which consists in removing material by grinding from plow body supporting portions of the frame to such extent that when predetermined plow 95 elements are attached thereto the plow bodies will be in true plowing relation to each other.

4. A standardized gang plow frame made by removing material therefrom to such 100 extent that when predetermined plow elements are attached thereto the plow bodies will be in true plowing relation to each other.

5. A standardized gang plow frame made by removing sufficient material from the plow body carrying portions thereof so that when predetermined plow elements are attached to said plow body carrying portions, 110 the plow bodies will be in true plowing relation to each other.

6. A standardized gang plow frame made by removing sufficient material by grinding from the plow body carrying portions thereof so that when predetermined plow elements are attached to said plow body carrying portions, the plow bodies will be in true 115 plowing relation to each other.

THEOPHILUS BROWN.
